UNITED STATES PATENT OFFICE.

FRANK P. GRODE, OF KANSAS CITY, MISSOURI.

DESIGN FOR A BILLIARD-TABLE LEG.

50,347.

Specification for Design.

Patented Feb. 20, 1917.

Application filed December 16, 1916. Serial No. 137,465. Term of patent 7 years.

To all whom it may concern:

Be it known that I, FRANK P. GRODE, a citizen of the United States, residing at Kansas City, in the county of Jackson and State of Missouri, have invented a new, original, and ornamental Design for a Billiard-Table Leg, of which the following is a specification, reference being had to the accompanying drawing, forming a part thereof.

In the drawing—

Figures 1 and 2 are front and rear perspective views, respectively, of a billiard table leg embodying the new design; and

Fig. 3 is a plan view of the same.

I claim:

The ornamental design for a billiard table leg, as shown.

FRANK P. GRODE.
